UNITED STATES PATENT OFFICE.

ASHTON P. DERBY, OF GARDNER, MASSACHUSETTS, ASSIGNOR TO P. DERBY & COMPANY, INC., OF GARDNER, MASSACHUSETTS, A CORPORATION OF MASSACHUSETTS.

CORNER-JOINT.

1,207,001.

Specification of Letters Patent.

Patented Dec. 5, 1916.

Application filed June 21, 1915. Serial No. 35,490.

To all whom it may concern:

Be it known that I, ASHTON P. DERBY, a citizen of the United States, and resident of Gardner, in the county of Worcester and State of Massachusetts, have invented new and useful Improvements in Corner-Joints, of which the following is a specification.

This invention relates to the construction of corner joints for furniture and similar articles, and while capable of use in articles of various kinds, where a rigid, tight joint is required, it is particularly designed as a corner joint for chair frames. For the purposes of illustration therefore an embodiment of the invention suitable for wooden chairs will be described, but it will be understood that the invention is applicable generally to other structures, and its more general application is contemplated in the claim.

In the accompanying drawings which illustrate one embodiment of the invention,—Figure 1 is a side elevation of a chair in which the improved corner joint is incorporated; Fig. 2 is a section on line 2—2 of Fig. 1, showing the joint members assembled and locked together; Fig. 3 is a similar sectional view showing the parts in position before the locking pins are inserted; Fig. 4 is a sectional view of the assembled parts on line 4—4 of Fig. 2; and Fig. 5 is a detail in section similar to that of Fig. 4, showing the parts before the locking pins are inserted.

The corner piece, which in this embodiment of the invention constitutes a leg of a chair, is shown at *a*, and the two angle members, constituting the side frames of the chair seat, are shown at *b*, *b*. The angle members *b*, *b* and corner member *a* may be united by a mortise and tenon joint or by other usual or suitable means.

c represents the cover or seat proper secured on the top of the frame members or angle members *b*.

Each angle member *b* is provided near its end with a narrow recess or slot *b'* formed in the inner face of the angle member *b*, and preferably extending only part way through the angle member. A hole *b''* intersecting the slot *b'* is formed in angle member *b*, and extends from one face thereof, preferably the lower face, part way through the member *b*.

d is a tie member or brace member prefer-

ably consisting of a flat metal plate, which is bent at its middle portion to form a channel *d'*, thus reinforcing and stiffening the tie member *d* at the part extending between the two angle members *b*, *b* for the purpose hereinafter described.

The tie member *d* is provided with holes *d''* at its ends, in such position that the distance between the holes *d''* is slightly less than the distance between the holes *b''* when the angle members *b*, *b* are assembled in the frame in normal position but before they are finally locked together by inserting the locking pins. Thus the holes *d''* and *b''* before locking will not register accurately but will overlap as best shown in Figs. 3 and 5.

Locking pins *e*, having tapering or beveled ends *e'*, are inserted into holes *b''* with their bevels facing outwardly or toward the ends of the tie member *d*, and when driven home through holes *b''* and holes *d''* the beveled surfaces *e'* will engage the sides of holes *d''* on the outer side or side toward the ends of the tie member, causing the holes *d''* to ride up the beveled surfaces *e'* on to the body parts of the pins *e*, thereby forcibly drawing the angle members *b* slightly toward each other and binding or compressing the angle member *b*, *b*, and corner piece *a* together in tightly locked relation under the resulting tension in tie member *d*.

The channel portion *d'* of the tie member is provided with a hole through which the screw *f* passes and is screwed at its end into the cover piece or seat *c*. The channeling of the tie member *d* at *d'*, along the part between the ends which are secured in the angle members *b*, stiffens and reinforces the tie member against the transverse strain applied thereto by the screw *f*. The frame members, thus united as best shown in Figs. 2 and 4, are therefore all securely bound and held together with the locking strain in all directions borne by the metal tie piece *d*.

I claim:

A corner joint for chairs comprising a leg; a pair of side frames connected to the leg and each formed with a narrow opposing slot in its inner face and a hole extending upwardly and partly through the frame and intersecting said slot; a substantially flat narrow strip of metal serving as a tie mem-

ber and extending between said side frames with its ends in said slots and having a hole at each of its ends, the distance between the holes in the side frame when assembled and in normal position being slightly greater than the distance between said holes in the tie member; and locking pins having tapering ends adapted when inserted in said holes

to bind and hold said angle members together.

Signed by me at Gardner, Massachusetts, this seventeenth day of June, 1915.

ASHTON P. DERBY.
